AQUARIUM AERATOR

Alfred Greenbaum, 159 E. 52nd St.,
Brooklyn, N.Y. 11203

Filed Oct. 17, 1968, Ser. No. 14,028

Term of patent 14 years

Int. Cl. D30—01

U.S. Cl. D30—12

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a side elevational view of an aquarium aerator embodying my new design;

FIG. 2 is a top plan view thereof;

FIG. 3 is a bottom plan view thereof;

FIG. 4 is a side elevational view of the opposite side to that shown in FIG. 1;

FIG. 5 is a front elevational view;

FIG. 6 is a rear elevational view;

FIG. 7 is a side elevational view of a modified form of an aquarium aerator as shown in FIG. 1;

FIG. 8 is a top plan view of FIG. 7;

FIG. 9 is a bottom plan view of FIG. 7;

FIG. 10 is a side elevational view of the opposite side to that shown in FIG. 7;

FIG. 11 is a front elevational view of FIG. 7; and

FIG. 12 is a rear elevational view of FIG. 7.

I claim:

The ornamental design for an aquarium aerator, substantially as shown and described.
